BEN THACKARA DESIGN FOR THE
BODY OF A SHADE FOR GAS OR LAMP BURNERS

Q-3878

Patent Mar. 11, 1870

Benjamin Thackara

WITNESSES: *W. E. Steel*
A. D. D. L.

United States Patent Office.

BENJAMIN THACKARA, OF PHILADELPHIA, PENNSYLVANIA, ASSIGNOR
TO MISKEY, MERRILL & THACKARA, OF SAME PLACE.

Design No. 3,878, dated March 1, 1870; antedated October 1, 1869.

DESIGN FOR SHADE FOR GAS OR LAMP-BURNERS.

The Schedule referred to in these Letters Patent and making part of the same.

I, BENJAMIN THACKARA, (assignor to the firm of Miskey, Merrill & Thackara,) of Philadelphia, county of Philadelphia, State of Pennsylvania, have originated a new Design for the Body of a Shade for Gas or Lamp-Burners, of which the following is a specification.

In the drawing—

The figure shown by the plain lines represents my design for the body of shade for gas or lamp-burners, and the dotted lines represent modifications of the design, which consists of the frustum of a cone, *b*, united at its base to that of a larger and inverted frustum of a cone *d d*, the latter terminating at the bottom in a flange for attaching the shade to a burner, which flange, however, forms no part of my design.

The two modifications, illustrated by dotted lines, vary as regards the length and inclination of the two frustums of cones from the design illustrated by plain lines.

I claim the design for the body of a shade for a gas or lamp-burner, substantially as described, and as illustrated in and by the accompanying drawing.

In testimony whereof I have signed my name to this specification in the presence of two subscribing witnesses.

BENJAMIN THACKARA.

Witnesses:

W. FRANK HEATH,
SAMUEL C. OGLE.
